United States Patent Office

Des. 228,991
Patented Nov. 6, 1973

228,991

BED

Margaret Ross Hinton, Box 572,
Mount Pleasant, Tex. 75455

Filed May 4, 1972, Ser. No. 250,471

Term of patent 14 years

Int. Cl. D6—01

U.S. Cl. D6—83

FIG. 1 is a front isometric view of a bed showing my new design.

FIG. 2 is an isometric view thereof showing the rear of the headboard and the footboard, and

FIG. 3 is a front elevational view thereof showing the front of the headboard and the footboard.

The dotted lines showing the bedspread and pillow are for illustrative purposes only.

I claim:

The ornamental design for a bed, substantially as shown.
